DEGREASING APPARATUS

Willard D. Phillips and Ralph A. Van Fossen,
Chicago, Ill.

Original application August 3, 1940, Serial No.
351,018. Divided and this application February
15, 1943, Serial No. 475,917

2 Claims. (CL 202—170)

This invention is a division of our co-pending application, Serial No. 351,018, filed August 3, 1940, and is an improvement on our degreaser fully described in our Patent 2,253,579 issued August 26, 1941. One of the objects of the invention is to provide a degreasing cabinet with a new and novel mechanical design wherein a cabinet of comparatively small size and weight is arranged to include a relatively large vapor treating chamber adapted to handle large and heavy machinery. 10

The particular object of the invention is to provide a novel vapor control combination comprising a vapor level control device to establish a normal vapor level within the vapor chamber, and a thermally active radiating surface on the exterior of the vapor chamber to increase surface radiation and thereby facilitate condensation of vapors above the normal vapor level. 15

Referring now more particularly to the drawing:

Fig. 1 is a side elevational view partly in section illustrating the novel means for controlling the vapor level in a degreaser chamber;

Fig. 2 is a wiring diagram of the electrical circuit of the typical degreaser apparatus;

Fig. 3 is a perspective view illustrating the application of the vapor control means on a modified type of cabinet; and

Fig. 4 is a fragmental sectional view taken substantially on the plane of the line 4—4 in Fig. 1. 30

Now referring to the drawing, the degreasing apparatus illustrated in Figs. 1 to 4 inclusive, includes a rectangular degreasing cabinet 151 or a cylindrical degreasing cabinet 152, either of which may be arranged to include the thermostatic vapor controlled devices more fully illustrated in our Patent No. 2,253,579, issued August 26, 1941, and which may also be provided with a new and novel means to assist in maintaining the uniform vapor level and preventing hydro-carbon vapors from escaping from the degreasing cabinet. The vapor chamber illustrated in Fig. 1 comprises a thin sheet metal cylindrical body portion 153 terminating at its upper extremity in a beaded reinforcing rim 154 and terminating at its lower extremity in a beaded rim 155 interconnecting with the bottom portion 156 of the chamber. The bottom portion 156 extends inwardly and is joined to the walls of a cylindrical chamber or vaporizing sump 157 at a point somewhat below the upper extremity of the cylindrical walls to provide an upstanding partition to define a distillate receiver or sump 158 between the cylinder 157 and the outer cylinder 153. The sump 157 has a bottom 159 having a shelf flange 161 in which a 35

heating element 162 is mounted. The entire unit is supported on three legs 163 preferably welded to the cylindrical vapor chamber 153 and provided with casters 164 or other friction-reduction devices to facilitate easy, convenient movement of the entire unit. 5

If desired, a cover may be provided and a flushing pump 165, including a sediment pump 166 and a manually operable flushing nozzle 167. These mechanisms form no pertinent part of the present invention, however, and will, therefore, not be described in further detail.

In any type of degreasing apparatus it is of utmost importance to provide a satisfactory means for controlling the vapor level and for preventing hydro-carbon vapors from escaping from the apparatus into the surrounding air. This is particularly true, of course, in an apparatus designed as a portable unit to be used in a crowded factory location in close proximity to other workers or in closed and comparatively poorly ventilated industrial plants. In this connection it is pointed out that in order to be satisfactory for use in a crowded factory building, it is essential that the hydro-carbon vapors utilized as the active element in degreasing equipment be properly and effectively confined within the degreasing apparatus, since the presence of undue vapors in the air introduces an unpleasant atmosphere, and if the concentration of vapors rises above a minimum, it may be actually harmful for persons working in the vicinity for long periods of time. This situation has been recognized by the public health authorities in practically every locality and almost every community has in effect public health regulations defining the maximum concentration of hydro-carbon vapors legally allowable in industrial locations. 20

It will be appreciated that although the hydro-carbon vapors used are approximately five times more dense than air, yet they are not sufficiently dense to satisfactorily operate float valves or other such devices commonly utilized to control fluid levels, but inasmuch as the body vapor within the chamber will always be at an exactly uniform temperature, and since any cooling of the vapor will reconvert it into liquid, this invention seeks to take advantage of these characteristics by providing vapor control devices including a thermostat 171 on the side wall of the vapor chamber 153 at a point substantially above the bottom of the chamber but substantially below the upper rim 154. As hereinbefore pointed out, the hydro-carbon vapors are approximately five times heavier than air and thus as the liquid is heated and 25 30 35 40 45 50 55

vapor begins to form, it will slowly rise to a uniform level throughout the chamber until the upper level of the vapor reaches the thermostat.

It is understood, of course, that the critical temperature of the thermostat 171 is adjusted to be below the boiling point of the solvent so that whenever the high temperature vapor contacts the thermostat, the thermostat may act through the electrical switch 172 to open the electrical circuit through the heating element 162 and prevent the further production of vapor. Similarly, as the vapor condenses by contact with the work or the side walls of the vapor cabinet, the vapor level will gradually fall until it is below the level of the thermostat 171. As this occurs the air from the atmosphere of the room will be drawn into the chamber and will contact the thermostat 171 and since this air is at a temperature far below the boiling point of the solvent, it will actuate the thermostat to again close the circuit through the heating element 162. The electric heating element 162 is also provided with a tubular temperature thermostat bulb 173 connected to the pressure switch 172 by an operating tube 174.

As thus far described, the vapor control devices are identical with those disclosed in our Patent No. 2,253,579, issued August 26, 1941, but in the present invention a substantial improvement in the efficiency of operation has been obtained by providing exterior surfaces of differing thermal characteristics on the outside of the vapor chambers 151 or 152. In small portable units it is essential that the wall structures be made of a single thickness of comparatively light sheet metal, as for example, the metal sheet 181 illustrated in Fig. 4, and this sheet metal is customarily galvanized or otherwise coated with corrosion-resisting material forming an interior layer 181 and an exterior layer 183. In case of ordinary galvanized metal these two layers are comparatively highly polished and tend to reflect the heat within the chamber rather than to radiate it into the outer air. Thus while a certain degree of condensation takes place on the walls 153, yet it is comparatively small because of the low radiating characteristics of the polished surfaces 182 and 183. The low radiating characteristics of the side walls 153 are ordinarily desirable, since an overly rapid condensation of the vapor on the side walls will of necessity call for a correspondingly large capacity of the heating unit 162 in order to maintain the solvent level at all times.

In the event that the solvent level should be disturbed, however, either by the introduction of large objects into the chamber or by violent currents of air in proximity to the apparatus, it is desirable to instantly condense any hydro-

carbon vapors which may tend to rise above the normal vapor level in order to prevent these vapors from escaping into the atmosphere. To accomplish this we provide a thermally active coating 184 on the exterior surface of the chamber 151 or 152 and extend it downwardly from the upper rim of the chamber to a point at the approximate level maintained by the vapor control thermostat 171. The thermally-active coating 184 may be of metallic or non-metallic composition and highly satisfactory results have been obtained by utilizing ordinary black paint, since the black surface of the portion 184 will have a considerably higher capacity for radiation than the bright galvanized surface 183. The higher radiating characteristics of the surface 184 will cause the upper portion of the side walls 153 to remain at a comparatively cool temperature at all times. Thus, in the event that the vapor level is disturbed, any swirling currents of vapor tending to rise above the rim of the cabinet will be effectively prevented from escaping since they will first strike the relatively cool side walls and be instantly condensed into liquid 25 which will drop into the receiving sump 159.

Having thus shown and described our invention, we claim:

1. In a degreasing apparatus, the combination of a vapor chamber, means to supply vaporized solvent within said chamber, vapor level control devices to establish a normal solvent vapor level in said chamber, and a radiating surface on the exterior of said vapor chamber above the normal solvent vapor level, said radiating surface being characterized by heat radiating properties greater than the heat radiating properties of other portions of the vapor chamber.

2. In a degreasing apparatus, a vapor chamber including side walls of thin, light sheet material having high heat conducting characteristics, said chamber having parallel, vertical side walls terminating at their upper extremity in an unobstructed mouth of area not substantially less than the area of the vapor chamber, a solvent vaporizing sump, an electrical heating unit in said vaporizing sump and adapted to be submerged in liquid solvent, a vapor-actuated control for said heating unit, said vapor-actuated control being positioned at a point substantially below the top of said side walls and substantially above the bottom of the vapor chamber, and a thermally-active coating on the exterior surface of the said vapor chamber walls above said control, said coating being characterized by heat radiating properties greater than heat radiating properties of the chamber walls.
